ARTICLE CARRIER

Filed July 23, 1927

FIG. 3.

INVENTOR.
H. V. Chandler

BY

Watson E. Coleman
ATTORNEY.

UNITED STATES PATENT OFFICE.

HARVEY V. CHANDLER, OF SULPHUR SPRINGS, TEXAS.

ARTICLE CARRIER.

Application filed July 23, 1927. Serial No. 208,022.

This invention relates to an article carrier adapted to be used upon the top of an automobile machine and it consists in the novel features hereinafter described and 5 claimed.

An object of the invention is to provide a carrier in the form of an attachment which is of simple structure and which may be easily and quickly manipulated for supporting light articles at the top portion of the body of the machine. The parts and features of the device are so arranged and assembled as to effectually hold the articles without damaging the same or distorting them out of 15 shape.

With this object in view, the structure includes strip members adapted to be applied to the sides of adjacent rods of the top structure, said strip members having oppositely 20 disposed hooks. The straps are disposed transversely across the sides and between the hooks. The said straps are folded upon themselves and are connected at the fold lines by means of springs with hooks upon one strip 25 and the said straps are provided at their ends with loops and buckles adapted to engage the hooks upon the other strip member.

In the accompanying drawings,

Figure 1 is a top plan view of the article 30 carrier,

Fig. 2 is a transverse sectional view thereof, Fig. 3 is a plan view of the hook member used in the carrier, and

Fig. 4 is an edge elevation of the hook member applied.

As illustrated in the accompanying drawing, the article carrier comprises strip members 1 preferably of metal, adapted to be applied to the sides of adjacent top bows 2. 40 The said strip members are provided with hooks 3. Straps 4, of webbing or elastic, are provided at one end with loops 5 which are adapted to engage the hooks 3 and the intermediate portions of the straps are passed 45 through loops 6 to which are connected the ends of coil springs 7. The outer ends of the springs 7 are hooked, as at 8, and the said hooked ends are adapted to be engaged with the hooks 3 carried by the opposite strip member 1.

The free end portion of each strap 4 is connected with a buckle frame 9 and the said buckles are especially adapted to be used in conjunction with a carrying device of this 55 character.

Each buckle frame is formed from a single length of rod 10, one end portion of the frame being in the form of a rectangular figure, preferably in the form of a square, and as indicated at 11, said figure having an open 60 center, as at 12. The material of the rod 10 is extended from one corner of the figure 11 in the form of an arcuate hook 13 and the free end of the said hook is spaced from the opposite adjacent corner of the figure 11. The hook 13 lies in the same plane as that in which the figure 11 lies. The free end portion of the strap 4 is carried under the figure 11 and the end of the strap is extended 65 around the inner side of the figure 11 and is then passed through the open center 12 and extended under the outer side of the figure 11 so that the extremity of the strap lies between the outer side of the figure 11 and the intermediate portion of the strap 4. 70 When the strap is so connected with the buckle frame 9, the hook 13 may engage over one of the hooks 3, but while the strap is in engagement with the figure 11 the said hook 3 cannot pass through the space between the 75 end of the hook 13 and the adjacent corner of the figure 11. The space between the end of the hook 13 and the adjacent side of the figure 11 is just sufficient to receive the strap 4 when moved edgewise across the frame 11 so that the end portion of the strap may be engaged around the inner side of the figure 11 without having to thread the extremity of the strap through the hook 13.

When the parts are connected with each other as hereinbefore described and the device is attached to the opposed sides of adjacent top bows, light articles may be interposed between the upper and lower portions of the straps and carried at the top of the 90 vehicle without danger of crushing the articles or distorting the press of garments which may be carried by the attachment.

Having described the invention, what is claimed, is:

1. An article carrier comprising strip members having opposed hooks, a strap connected at one end with one hook, a longitudinally extensible spring slidably connected with the intermediate portion of the strap and adapted to be connected with an opposite hook, and a hook frame carried at the free end of the strap and adapted to be detachably connected with the first mentioned hook.

2. An article carrier comprising strip mem-

bers having opposed hooks, a strap member having at one end a loop engaging one of the hooks, a second loop slidably mounted upon the intermediate portion of the strap, a longitudinally extensible spring connected with said second loop and adapted to be connected with an opposite hook, and a hook frame having a rectangular end portion adjustably connected with the free end of said strap, said hook frame having a hooked extremity adapted to engage the first mentioned hook.

3. In an article carrier, parallel members having pairs of opposed hooks, a plurality of flexible loops each secured to a hook of one of the members and a spring slidably engaging each loop at one end and having its opposite end engaged with the hook of the pair which is secured to the other of the members.

In testimony whereof I hereunto affix my signature.

HARVEY V. CHANDLER.
